United States Patent Office.

IRA YEAMANS, OF BROOKLYN, NEW YORK.

Letters Patent No. 104,010, dated June 7, 1870.

IMPROVED TEA AND COFFEE-SERVICE.

The Schedule referred to in these Letters Patent and making part of the same.

To all whom it may concern:

Be it known that I, IRA YEAMANS, of Brooklyn, in the county of Kings and State of New York, have invented a new and useful Improvement in Tea and Coffee-Services, of which the following is a full, clear, and exact description, reference being had to the accompanying drawing forming part of this specification, and in which—

Figure 1 represents a sectional elevation of a tea and coffee-service constructed in accordance with my invention, and

Figure 2, a plan of the same.

Similar letters of reference indicate corresponding parts.

This invention relates to tea and coffee-services, arranged on stands, and consists in a novel arrangement of the several vessels making up a service on a horizontal turn-table, around a central vertical axis in contradistinction to over it, in combination with a trunnion support of said vessels, or certain of them.

Prior to describing my improvement, it may here be premised that coffee-pots and other similar vessels have previously been arranged on horizontal turn-tables and suspended by trunnions, so as to be capable of being tilted or swung vertically, as described in Letters Patent No. 91,696, issued to me June 22, 1869; but, in such previous arrangement, said vessel has been placed directly over the axis of the turn-table, and the structure has only been adapted to a single vessel.

The structure represented in the accompanying drawing is very different, and comprises an entire tea and coffee-service, including a coffee-pot, A, tea-pot B, hot-water pitcher C, milk-pitcher D, sugar-bowl E, and slop-bowl F, all arranged upon a horizontal turn-table, G, around the vertical axis thereof, the sugar-bowl, slop-bowl, and milk-pitcher being removable from sockets or pockets on or in the face of the turn-

table, while the coffee, tea, and hot-water pots are hung by trunnions b b, to swing in standards H H, fast on the face of said table, with the spouts or mouths of said vessels facing outward to facilitate their use, by tilting, to pour from them into a tea or coffee-cup, as required, the turn-table having been previously rotated to bring the required vessel opposite the person using the service.

The horizontal turn-table G is supported and guided or restrained from shake by a lower vertical stem, I, resting on a center below and working in a socket, J, fast to a base portion, K; this insures an easy or frictionless run of the table.

Mounted on the turn-table G at its center, and secured to it in any suitable manner, is an upper stem, L, carrying at its top a disk, M, having locking recesses c made in and around its border, for spoons N, which may be entered edgewise through the recesses and then turned to leave them pendent on the disk, as represented in fig. 1. This spoon-holder will be found an additional convenience of no small importance.

What is here claimed, and desired to be secured by Letters Patent, is—

1. A revolving tea and coffee-service, having its several vessels arranged on a horizontal turn-table, G, in eccentric relation to the axis of the latter, and said vessels or certain of them being suspended by trunnions to swing vertically, substantially as specified.

2. The combination of the swinging pots or vessels A, B, and C, with the stationary vessels D, E, and F, the turn-table G, the base K, center supporting-stem I, and socket J, essentially as shown and described.

IRA YEAMANS.
